FACE MUSCLE LIFTER

Julius Thiemann, Mount Vernon, N. Y.

Application May 18, 1942, Serial No. 443,329

7 Claims. (Cl. 128—76)

This invention relates to new and useful improvements in a face muscle lifter.

More particularly, the invention contemplates characterizing the face muscle lifter by a pair of clasps adapted to be mounted on strands of hair at the temples, and strings from said clasps extending towards each other and adapted to extend over the head and be connected together so as to draw up the muscles along the sides of the face extending from the temples to below the chin.

More particularly, the invention contemplates a certain construction of each of the clasps adapting them to be effectively connected with the strands of hair and maintain their positions. It is proposed to construct these clasps of small size so that they may be mounted on the hair and allowed to remain thereon during shampooing, washing, etc.

A further object of the invention resides in the provision of a certain spring lock means associated with the strings from the clasps by which the strings may be held under tension for lifting the face muscles, as already stated.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an illustration of a face muscle lifter constructed according to this invention and applied to a patron.

Fig. 2 is a developed view of the face muscle lifter, per se.

Fig. 3 is a fragmentary perspective view of one of the pair of clasps of the face muscle lifter illustrated mounted on the strands of hair.

Fig. 4 is a rear elevational view of Fig. 3.

Fig. 5 is a view similar to Fig. 4 but showing the leaves of the clasp open.

Fig. 6 is a perspective view of the string lock means.

Fig. 7 is a vertical sectional view taken on the line 7—7 of Fig. 6.

Fig. 8 is a view similar to Fig. 7 but with the parts in a different position.

Fig. 9 is a similar view to Fig. 3 but illustrating a modified form of the invention.

The face muscle lifter, in accordance with this invention, includes a pair of clasps 10 adapted to be mounted on strands of hair 11 at the temples. Strings 12 and 13 from the clasps 10 extend towards each other and are adapted to extend over

the head 14 of a patron. String lock means 15 is associated with the strings 12 and 13 for holding the strings under tension for lifting the muscles at the sides of the face from the vicinity of the temples down to the chin.

Each clasp 10 comprises a pair of leaves 16 and 17 connected together at one of their ends by a hinge construction 18. The other ends of these leaves are provided with complementary latch elements 19 and 20 which engage each other when the clasp is closed for holding the leaves adjacent each other. It is proposed that the clasps 10 be mounted on the strands of hair 11 in a certain way. A small area of hair, for example $\frac{1}{4}$ of a square inch is collected and combed straight. Then at points 11^a near the roots of the hair the strands 11 are extended across the outer face of one of the leaves, as illustrated, the leaf 16, and over the top edge of this leaf 16 at the point 11^b. From this point the strands 11 are continued down across the back side of the leaf 16 and then at the point 11^c across the root ends 11^a of the strands of hair.

The strands of hair 11 are then continued upwards across the back of the leaf 16 as indicated by reference numeral 11^d. The top and bottom edges 21 of the leaf 16 are concave so as to tend to cause the strands of hair 11 to accumulate at the center of the leaf. The adjacent contracting faces of the leaves 16 and 17, when the clasp is closed may be knurled, or roughened in any other way, so as to better grip the strands of hair. When the leaves 16 and 17 are closed it will be found that the clasp is firmly mounted on the strands of hair 11. The top and bottom edges of the leaf 17 are also concave for purpose of ornamentation. The leaf 17 of each clasp has a hook 22 mounted on its top edge which is adapted to be engaged by one of the strings 12 or 13.

The string-lock means 15 comprises a hollow casing 23 having a felt bottom pad 24 for resting against the head. A stem 25 is slidably mounted within the casing and projects from one side. This stem has a head 26 by which it may be shifted inwards and outwards. The inner end of the stem 25 is slidably supported in a block 27. The inner end of the stem 25 has an offset inner end 28 passing through a slot 29 in the block 27 for limiting movement of the stem. A bolt 30 is slidably mounted through the top wall of the casing 23. The bolt 30 passes through a leaf spring 31 located on the top of the casing 23. The bolt 30 has an inner head 32 which is engageable by a cam 33 on the stem 25. The stem 25 has a slot 34 through which the bolt 30 passes. The cam 33 is located

to the sides of the bolt 30 and engages against the head of the bolt, as clearly shown in Fig. 7. When the stem 25 is pulled outwards, as illustrated in Fig. 8, the cam 33 rides free from the head 32 of the bolt 30, and then the leaf spring 31 is loose.

The string 12 is provided with a loop 35 at one end which is engaged on one of the hooks 22 of one of the clasps 10. The other end of the string 12 is tied through apertures 36 formed in the casing 23. The string 13 is doubled upon itself. One end is tied through apertures 36 to the casing 23. The intermediate portion of the string 13 is engaged through the hook 22 of the clasp 10, the free end of the string 13 is engaged beneath the spring 31 which fixedly holds it in position.

The operation of the face muscle lifter may be understood from the following: The clasps 10 are mounted upon strands of hair at the temples. The strings 12 and 13 are then extended over the head. The string 13 is pulled tight so as to tension the strings 12 and 13. This pulls the strands of hair upon which the clasps 10 are mounted. The tension is transmitted to the face muscles, lifting the muscles long the sides of the face all the way down to the chin.

The face muscle lifter may easily be removed by first pulling outward on the head 26 so as to extend the stem 25 to the position shown in Fig. 8. This releases the leaf spring 31 which frees the string 13. This loosens the strings 12 and 13 and facilitates disengagement of the strings from the hooks 22 of the clasps 10. The clasps 10 may be removed from the strands of hair 11 when desired.

In Fig. 9, a clamping member 40 is provided for reinforcing the grip of leaves 16 and 17 on the strands of hair 11. The clamping member 40 consists of a pair of substantially parallel arms 41 joined by a loop portion 43 which is adapted to be engaged by the strings 12 and 13. The free ends of the clamping member 40 are bent down, under the arms 41 and towards the loop portion 43, so as to hold the clasp 10 in addition to facilitate the gripping of the strands of hair 11.

This arrangement permits the removal of the strings 12 and 13 together with the gripping members 40, without manipulating the string lock 15.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A face muscle lifter comprising a pair of clasps adapted to be mounted on strands of hair at the temples, strings from said clasps extending towards each other and adapted to extend over the head, and string-lock means associated with said strings for holding said strings under tension, for lifting the muscles at the sides of the face, each of said clasps comprising a pair of leaves hingedly connected together and latch elements for holding them closed, said leaves having concave top and bottom edges, a gripping member anchored at the outer faces of the said pair of clasps to facilitate gripping the strands of hair, a loop portion, integral with the said gripping member for holding the ends of the said strings, said gripping member comprising a pair of par-

allel arms joined by the said loop portion and a pair of downwardly and backwardly bent resilient free extensions for gripping said clasp.

2. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing.

3. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing, said slidably mounting of said spring, comprising a bolt having its head disposed within said casing and the free end of its shank slidably projected from the top wall of said casing and said spring being mounted on the outer end of said shank.

4. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing, said slidably mounting of said spring, comprising a bolt having its head disposed within said casing and the free end of its shank slidably projected from the top wall of said casing and said spring being mounted on the outer end of said shank, said means, comprising a stem slidably disposed within said casing at right angles to said bolt and formed with a slot through which said shank passes, and a cam mounted on said stem and engaging the adjacent face of the head of said bolt to hold said bolt against moving outwards.

5. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing, said slidably mounting of said spring, comprising a bolt having its head disposed within said cas-

ing and the free end of its shank slidably projected from the top wall of said casing and said spring being mounted on the outer end of said shank, said means, comprising a stem slidably disposed within said casing at right angles to said bolt and formed with a slot through which said shank passes, and a cam mounted on said stem and engaging the adjacent face of the head of said bolt to hold said bolt against moving outwards, said stem having an end projected from said casing by which said stem may be pulled outwards to disengage said cam from said head and free said bolt to move outwards.

6. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing, said slidable mounting of said spring, comprising a bolt having its head disposed within said casing and the free end of its shank slidably projected from the top wall of said casing and said 30

spring being mounted on the outer end of said shank, said means, comprising a stem slidably disposed within said casing at right angles to said bolt and formed with a slot through which said shank passes, and a cam mounted on said stem and engaging the adjacent face of the head of said bolt to hold said bolt against moving outwards, said stem having an end projected from said casing by which said stem may be pulled outwards to disengage said cam from said head and free said bolt to move outwards, and means limiting movement of said stem to positions in which said cam engages or is disengaged from said head.

15 7. A face muscle lifter having a pair of clamps adapted to be mounted on strands of hair at the temples and strings extending from said clamps to be directed towards each other over one's head, a casing positioned at the top of one's head, one of said strings having its free end securely attached to said casing, a leaf spring slidably mounted on said casing and adapted to have the free end of the other of said strings adjustably connected therewith, and means holding said leaf spring against said casing for clamping the free end of said latter string between the adjacent faces of said spring and casing, and a felt pad mounted on the bottom face of said casing for resting against the wearer's head.

JULIUS THIEMANN.
